UNITED STATES PATENT OFFICE.

ABRAHAM ABRAHAM, OF BROOKLYN, NEW YORK.

PACKING-BASKET.

SPECIFICATION forming part of Letters Patent No. 595,685, dated December 21, 1897.

Application filed March 15, 1897. Serial No. 627,483. (No model.)

To all whom it may concern:

Be it known that I, ABRAHAM ABRAHAM, a citizen of the United States, residing at Brooklyn, in the county of Kings and State of New York, have invented a certain new and useful Improvement in Packing-Baskets, of which the following is a specification.

Heretofore serious objection has been found to packing-baskets employed particularly for the packing of crockery and like articles which require hay, excelsior, or like material between the articles packed in that when the same was unpacked at the house of the purchaser the apartment was apt to be littered, and upon returning to the seller or vender, where the baskets would frequently be left on the street owing to the inability to handle them quickly, the wind would scatter the hay, &c., much to the displeasure and inconvenience of passers by and to the dirtiness of the street.

The object of my invention is to provide a basket which will avoid these objections, and I accomplish my object by providing a fabric covering secured adjacent to the rim of the basket proper in any convenient or suitable way, which fabric is of more than sufficient dimensions to cover the opening of the basket, and is itself provided with an opening, into which is let eyes and a draw-cord, whereby the opening of the fabric may be drawn tightly together, thereby inclosing the entire contents of the basket. I also provide openings in the fabric or covering when it is secured to the outside of the basket, so that the handles of the basket may project through and be readily reached for the purposes of carrying the same.

In the accompanying drawing, forming part of this specification, the single figure shows a perspective view of the basket and its attached cover closed, with the approximate position of the cover when open shown in dotted lines.

45 A in the drawing is the basket, provided with handles B B.

C is the cover, which, as shown, is attached to the outer edge of the basket by means of a binding-wire D, the ends of which are

twisted together, as shown at x, so as to bind 50 the cover tightly to the basket. Holes E E are provided, through which the handles project, and, as shown, a central opening is formed in the cover, which is provided along its margin with eyelets F and a running or 55 draw string G.

Preferably the dimensions of the cover from the point of binding at the rim of the basket to the central opening should be such that the edges of the opening will overlap 60 when the basket is filled only to the rim, and hence will permit the basket to be filled above the rim, the surplus of material permitting this.

It will be seen now that in unpacking the 65 basket the packer may hold the cover, which is preferably of burlap, in such a way as to confine the hay, excelsior, &c., within the basket owing to the height of the cover when its opening is distended. Hence the packing 70 material will not litter the apartment. After the unpacking has been completed, the packing material remaining in the basket if the packer has been a careful man, the cover will be drawn together over the packing, and the 75 possibility of its being scattered by the wind or otherwise will be avoided. I have found in practice that this character of basket is a very great convenience and saves a great deal of annoyance and dirt. 80

I claim—

The combination of a packing-basket with a cover therefor consisting of a strip of material of uniform width, joined at the ends and attached near the edge of the basket- 85 opening on the outside of the basket, said cover having openings therein for the handles of the basket, a binding-wire for retaining said cover in place and a running cord passing through eyelets in the unattached edge 90 of said strip, substantially as set forth.

This specification signed and witnessed this 6th day of March, 1897.

ABRAHAM ABRAHAM.
